MULTIPLE FLUID AIRBRUSH

Jens A. Paasche, Chicago, Ill.

Application January 12, 1945, Serial No. 572,516

1 Claim. (Cl. 299—140)

1

The present invention relates to a multiple fluid airbrush of the type capable of projecting a plurality of different liquids.

Heretofore it has been found convenient in certain spraying and coating operations to apply a coating by separately spraying several of the ingredients. For example in the application of latex, two different liquids are applied to provide a more satisfactory coating. Similarly in the application of certain paints and plastic compounds two different liquids are projected in a mist toward the object to be coated to provide a more uniform and more satisfactory coating. Heretofore relatively complicated double spray heads have been provided for such operations. While in certain instances it may be of some advantage to employ such arrangement, in many other instances it is deemed that such complicated structure is difficult to handle and is expensive to manufacture. Therefore in accordance with the present invention a relatively simple arrangement is provided whereby a plurality of fluids are readily controlled in order to project a coating and the like.

It, therefore, is an object of the present invention to provide an improved multiple fluid airbrush which is relatively simple to manufacture and to operate.

Other and further objects of the present invention subsequently will become apparent by reference to the following description taken in connection with the accompanying drawing wherein.

Figure 1 is a side view of a multiple fluid airbrush constructed in accordance with the present invention;

Figure 2 is a cross sectional view of a portion of the apparatus shown in Figure 1 as seen in the direction of the arrows along the line 2—2;

Figure 3 is a cross sectional view of the apparatus shown in Figure 1 as seen in the direction of the arrows along the line 3—3;

Figure 4 is a cross sectional view of Figure 1 looking forwardly along the line 4—4 in the direction of the arrows;

Figure 5 is a perspective view of the cylindrical body portion of the apparatus shown in Figure 1;

Figure 6 shows a handle supporting element.

Referring to the drawing it will be seen that there has been provided a multiple fluid airbrush comprising a generally cylindrical body 10 which has a forwardly threaded portion 12 and a rearwardly threaded portion 14. Extending toward the rear of the gun beyond the threaded portion 14 is a coaxial member 16 of lesser diameter

2

arranged to serve as a support for a valve actuating mechanism. The body 10 is provided adjacent its underside with an elongated slot 18 connected to a narrower slot 20. The narrower slot 20 receives the handle supporting member 22 which extends through a suitable handle 24 readily secured in position by a nut 26 engaging the threaded portion 28 of the supporting member 22. Adjacent the upper end of the handle 24 there is provided an adjusting screw 30 which controls the degree of actuation of a trigger 32. The trigger is pivotally mounted from a cross pin 34 at an intermediate point on the body 10. The trigger 32 has at an intermediate point a recess 36 which engages the end of an actuating member 38 having at its other end a ball portion 40 supported within a socket member 42. The socket member 42 is arranged at the end of a cylindrical member or rod 44 connected to a valve member 46. The valve member 46 is biased toward closure by a suitable spring 48 bearing against a screen 50. The valve 46 cooperates with a valve seat 52 formed in a valve supporting member 54 which engages the threaded portion 14 of the body 10. The screen 50 against which the spring 48 bears is retained in position by a threaded ring 56. The member 54 adjacent its outer end is adapted to be engaged by a threaded ring nut 58 for connecting a suitable flexible conduit or hose 60 thereto. The hose or conduit 60 is arranged to be connected to a fluid under pressure.

The space between the end of the cylindrical body member 10 and the inside of the valve supporting member 54 which forms a chamber 62 is connected by a conduit 64 shown in Figure 1 to a coaxial opening 66 more readily seen in Figures 2 and 3. The forward end of the body 10 is connected by a threaded ring 68 to a suitable coupling member 70 which engages a multiple passage head 72. The multiple passage head has a passage 74 communicating with the coaxial passage 66 of the body 10. The passage 74 terminates in an internal nozzle 76. The other fluid passages 78 and 80 are connected by a suitable coupling means 82 and 84 to flexible fluid conduits 86 and 88 each of which is connected to a different fluid source of liquid. Interposed in the fluid conduits 78 and 80 are valve seats 90 and 92 adapted to be engaged by valves 94 and 96. Each of the valves 94 and 96 is manually adjustable so that the amount of liquid or fluid passing through the conduits 78 and 80 may be controlled thereby permitting a different propor-

tion of the different fluids to be projected by the apparatus.

Just above the valve seats 90 and 92 the member 72 is enlarged to provide annular chambers 98 and 100 communicating with forwardly extending fluid passages 102 and 104. The passages 102 and 104 terminate adjacent the interior nozzle 76. The combining nozzle 106 is retained in position by a suitable fastening or coupling ring 108. The nozzle 106 serves to project the two liquids or fluids supplied from the conduits 78 and 80 by virtue of the fluid projected through the interior nozzle 76, which fluid is controlled by the manual actuation of the trigger 32. The valve head 94 is supported by a valve stem 110 which is surrounded by a resilient gasket-like member 112. The valve stem 110 is adjustably positioned by virtue of the threaded portion 114 of the valve position adjusting member which terminates in a calibrated thumb screw 116 cooperating with a suitable graduation such as 118 on the side of the member 72. The resilient rubber-like gasket 112 serves to maintain the valve in any desired manually adjusted position. Similarly the valve head 96 is secured to a valve stem 120 which in turn is surrounded by a resilient retaining gasket or member 122. A threaded portion 124 interconnects the valve stem with the manually adjustable screw member 126.

In operation the conduit 66 is normally connected to a source of fluid such as air under pressure. Each of the other conduits 78 and 80 is connected to a suitable source of fluid or liquid of a characteristic dependent upon the type of coating to be applied to an object. By adjustment of the screw members 116 and 126 the proportion of the two materials or fluids may be regulated so as to provide the desired characteristics to the coating. The projection of the coating material is started and stopped by manual actuations of the trigger 32 which controls the opening and closing of the valve comprising the valve seat 52 and valve head 46 interposed between the fluid conduit 66 and the fluid conduit 64 contained within the body 10. The amount of fluid under pressure supplied by the actuation of the trigger 32 is controlled by the adjustment of the stop screw 38 positioned on the forward surface of the handle 24. The handle 24 which is held in position by the bolt-like member 22 is retained in position by the nut 26 engaging the threaded end portion 28 of the bolt-like member 22. In the other extremity the supporting member 22 is provided with a head portion 128 immediately beneath which there is a reduced or recessed portion 130 so that the head will fit within the body 10 and the reduced recessed portion fits between the sides of the narrow slot 20 shown in Figure 5.

While for the purpose of illustrating and describing the present invention a preferred embodiment has been shown, it of course will be appreciated that such variations are contemplated in the components and in their arrangements as may be commensurate with the spirit and scope of the invention defined in the following claim.

This invention is hereby claimed as follows:

A removable nozzle assembly for use with an air brush of the type having a valve controlled

passage therethrough for a propelling fluid; and comprising an elongated head member adapted to be secured to the air brush and having a longitudinal fluid passage therethrough adapted for communication with the fluid passage in the air brush, said head member having parallel bores therethrough disposed on opposite sides of said fluid passage and extending transversely thereof and each adapted for connection to a material supply line, said transverse bores having valve seats intermediate the ends thereof and said head member also having material passages each communicating with one of said bores and extending forwardly through said head member on opposite sides of said fluid passage and opening at the front end of said head member, separate valve members, one for each of said transverse bores cooperating with the seat therein for selective and permissive differential control of the passage of material through said bores to said material passages, an internal nozzle member detachably mounted at the forward end of said head member in communication with the longitudinal fluid passage therethrough and with the outer inwardly convergent surface thereof disposed inwardly between the outlet ends of said material passages, and an external nozzle detachably mounted at the forward end of said head member exteriorly of the said material passages and having the inner wall surface thereof sharply converging inwardly in advance of the adjacent surface of said internal nozzle to provide therebetween a confined mixing chamber with the inner wall surface of said external nozzle serving to sharply direct the material from the outlet ends of said material passages inwardly into said mixing chamber whereby the materials are mixed therein before being propelled through the second nozzle by the fluid under pressure issuing from said longitudinal fluid passage.
